MOLD FOR CONFECTION

Geraldine D. Williamson, Anderson, Ind.

Application May 9, 1955, Serial No. 35,890

Term of patent 14 years

(Cl. D44—1)

Fig. 1 is a view in perspective of a mold for confection showing my new design.

Fig. 2 is an exploded elevational view.

I claim:

The ornamental design for mold for confection, as shown.
